UNITED STATES PATENT OFFICE.

MYRON COSSEY, OF NEW YORK, N. Y., ASSIGNOR TO RELIANCE BALL-BEARING DOOR HANGER CO., OF NEW YORK, N. Y., A CORPORATION OF NEW YORK.

DOOR-HANGER.

1,002,902.

Specification of Letters Patent. Patented Sept. 12, 1911.

Application filed October 2, 1906. Serial No. 337,105.

To all whom it may concern:

Be it known that I, MYRON COSSEY, a citizen of the United States, and resident of the city of New York, borough of Brooklyn, 5 county of Kings, State of New York, have invented certain new and useful Improvements in Door-Hangers, of which the following is a specification.

This invention relates to door hangers, 10 and the object of the invention is to provide a simple and efficient hanger in which anti-friction devices are interposed between the bar from which the door is suspended and the fixed bar or track which supports the 15 door in its lateral movements. The anti-friction devices will preferably be balls and the track bar and rider-bar will have semi-circular grooves in their opposing edges for receiving the balls. Also a spacing bar, of 20 greater length than the rider-bar is employed to maintain the balls in relative position to each other and thus insure a proper support for the door throughout the extent of its movement, and means are provided to 25 prevent the spacing-bar from lifting and maintain it in substantially horizontal position between the track-bar and the rider-bar and out of contact with both.

Another object of the invention is to provide 30 an improved connecting device between the door and its rider-bar.

In Patent No. 809,781, granted to me January 9th, 1906, I have illustrated and described a hanger comprising three parallel bars of which the two outer bars are fixed 35 and constitute track-bars, and the middle bar constitutes the rider-bar for the door and moves between the track-bars. In this case balls are interposed between the middle 40 bar and the two outer bars and spacing-bars, or carriers, are employed to keep the balls in relative position. While this hanger may be used with any kind of laterally movable door, it is especially well adapted for use 45 with doors where it is essential to prevent any vertical or lateral movement of the upper part of the door at any angle to its normal path of movement. Elevator doors may be cited as an example and particularly 50 those which are opened automatically by the moving elevator. There are, however, many cases where it is not essential to prevent the movements above described but merely to limit them, while at the same time providing 55 for easy and rapid lateral movement of the

door and in such cases less expensive hangers than that illustrated in said patent may very advantageously be employed, and which will meet all requirements under normal and ordinary conditions. Sliding doors, 60 in private residences, offices, etc., may be cited as illustrations, and, in fact, any sliding door not liable to be subjected to abnormal strains may very advantageously be suspended by hangers constructed in accordance with my present invention. 65

I will now proceed to describe a preferred embodiment of my invention, reference being had to the accompanying drawings in which:—

Figure 1 is an elevation of a portion of a 70 door suspended by my improved hanger; Fig. 2 is an end view of the track and its support; Fig. 3 is a sectional view on the line 3—3 of Fig. 1; and Fig. 4 is a perspective view of the spacing-bar. Fig. 5 is a 75 sectional detail.

In these drawings 10 designates the track-bar which is adjustably supported at each 80 end by angle-brackets 11, the vertical members of which are secured to any suitable support, by screws or bolts 13. The horizontal member of each angle-bracket is provided with a threaded hole to receive a set-screw 14, the end of which engages the lower 85 edge of the track-bar, and the latter is provided near each end with an elongated slot 15 through which a set-screw 16 passes into the vertical member of the angle-bracket and serves to clamp the bar against such 90 member.

17 designates the rider-bar which is connected to the door by hangers. A preferred 95 form of connecting device is illustrated and consists of two vertically extending arms 18, connected at their lower ends in any suitable manner to a bar 19 which rests upon the top of the door. This connecting device is secured to the door by means of a plate 21 which extends between the arms and is provided with a transverse groove to receive the base 19 in such manner that the plate will rest upon said base and also upon the top of the door. As shown the plate extends beyond the arms on each side thereof, and is 100 secured to the door by screws 20 or other devices. The plate may also be recessed on the sides to receive the arms 18, so that the side edges of the plate will be flush with the outer faces of the arms. The plate in 110

effect constitutes an extended base-support for the arms. This construction provides a secure and rigid connection between the door and the connecting-device and, by reason of the extended base, materially decreases the liability of the device becoming loose and permitting the door to sag. The arms 18 straddle the track-bar and the rider-bar and are secured at their upper end to the latter by bolts or rivets 23, spacing-blocks 24 being preferably interposed between the arms 18 and the bar 17 to provide spaces between the arms and the track-bar.

The bars 10 and 17 have semi-circular grooves in their opposing edges to receive the balls 25. Any number of balls may be used, depending upon the width of the door, and preferably there will be a sufficient number so arranged that two or more, and preferably more, will always be between the track and the rider bars. In the present case six balls are shown, and are so arranged that at least three and sometimes four will be between the bars no matter what the position of the door may be. In order to maintain the balls in proper relative position I employ what I shall term a spacer, and which consists of a flat metal bar 26 of less thickness than the space between the bars 10 and 17, when the balls are between them. This bar is provided with a series of tapered holes 27 which are preferably uniformly spaced apart and of a diameter at the lower side of the spacer slightly greater than that of the balls, and at the upper side of the spacer slightly less than that of the balls in order that the balls may turn in said holes without undue friction, but at the same time be prevented from jumping out 40 of the spacer.

As shown, the length of the rider-bar 17 is substantially equal to the width of the door and in ordinary cases the range of travel of the door will be equal to twice its width. The balls and the spacer will normally travel at half the speed of the door and consequently the balls and spacer will move only half the distance the door moves. In order, therefore, to have a substantially uniform anti-friction support for the rider bar throughout its length and throughout the extent of its movement it is necessary to have the spacer longer than the rider-bar in order that the rider-bar when it passes off one ball will move on to another. If it were intended that one end of the spacer should be in the same vertical plane as one end of the rider-bar when the door is at its extreme position then the length of the spacer should be one and a half times that of the rider-bar. As shown however, the spacer-bar stops at a point somewhat short of that at which the rider-bar stops and, consequently, its length is less than one and a half times 65 the length of the rider-bar. The relative

length shown in the drawing have, in practice, been quite satisfactory and six balls arranged as shown have given excellent results in the easy running of the door. The spacer may, however, be relatively longer or shorter than as shown, and more or less balls than six may be employed with good and perhaps better results, and I therefore do not limit myself to exact proportions of length of the spacer and rider-bar so long as the former is substantially longer than the latter, nor to the number of balls, so long as there are enough, properly spaced apart, to insure at least two between the rider-bar and the track-bar throughout the full extent of the movement of the rider-bar. A preferable construction is however, one in which half the number or more of the balls employed will always be engaged by the rider-bar, and also one in which at least one of the balls will be disengaged by the rider-bar in any point in the movement of the latter.

It is not essential that the length of the rider-bar be equal to the width of the door, although I prefer that it should be, because it insures a perfect balance of the door. Good results, however, can be attained with a rider-bar of less length than the width of the door.

To obtain the best results in the easy running of the door it is desirable that the spacer 26 shall not engage either of the bars 10 or 17, which would cause considerable friction and retard the movement of the door, and, further, that it be maintained substantially horizontal or parallel to the bars 10 and 17. For this purpose I provide what may be termed a supporting and holding device, arranged as shown at each end of the spacer, which devices will support the spacer out of contact with the track-bar and hold it against upward movement to engage the rider bar. As shown, these holding and spacing devices are formed of flat strips of metal having a middle portion 28 and end portions 29 and 30 extending at right angles therefrom. The end portion 29 of each device is riveted or otherwise rigidly secured to the spacer on its upper surface, one being at each end thereof, and each end portion is provided with a hole 31 of less diameter than the holes 27 in the spacer and also less than that of the balls 25 and the ball will project through the hole 31 sufficiently to be engaged by the bar 17 and prevent engagement between said bar and the spacer. Since the holes 31 are of less diameter than that of the balls 25, it is obvious that the spacer will be supported by the end balls and consequently there will be no friction between the spacer and the bars 10 and 17. The other end portion 30 extends under the track-bar 10 just out of contact therewith but close enough thereto to 130

prevent any material upward movement of the spacer at either end. The middle portion 28 of each supporting and holding device may extend parallel to either the front 5 or the rear face of the track-bar 10 and will be out of engagement therewith. Obviously, instead of having the supporting and holding devices arranged over the two end balls they may be arranged over any other two 10 balls of the series.

Preferably, each hanger will be provided with a rivet or pin 32 secured in the arms 18 below the track-bar 10, out of engagement therewith but sufficiently close thereto to 15 prevent upward movement of the door sufficient to disengage the rider-bar from the balls 25.

Any suitable means may be employed to limit the movement of the door in either 20 direction and I do not deem it necessary to illustrate any special means.

In order to prevent the balls and spacer from running beyond the ends of the track-bar, I provide stops 33 on the track-bar 10, 25 near each end thereof, in the path of movement of the spacer and balls. These stops may be secured to the bar in any suitable manner.

The object of having the track-bar vertically adjustable is to enable it to be raised 30 at either or both ends in the event the door binds at the bottom from any cause whatsoever. Also sometimes it may be desirable to elevate one end of the track-bar in order 35 that the door may move in one direction by gravity.

Having described my invention I claim:—

1. In a door hanger, the combination of a fixed track-bar, a rider-bar to which the 40 door may be connected, a series of balls between the track-bar and rider bar, a spacer having openings in which said balls are loosely retained and may freely turn, bearings in said spacer, and additional supporting 45 balls fitting said bearings and traveling on said track bar whereby the spacer is held out of contact with both bars.

2. In a door-hanger, the combination of a fixed track-bar and a rider bar, to which 50 the door may be connected, said bars having grooves in their opposite edges, balls in said grooves, a spacer of greater length than the rider-bar interposed between said bars and having openings therein within which the 55 balls are loosely retained and may freely turn, and means for supporting the spacer out of contact with both bars comprising additional balls traveling on said track bar.

3. In a door hanger, the combination with 60 a door, of a fixed track-bar and a rider-bar, of a connecting device comprising two vertical arms which straddle said bars and are connected at their upper ends to the rider-bar, a base to which the lower ends of the 65 bar are connected and which rests upon the

door, a plate extending between said arms above the base and beyond said arms on each side, and means for securing said plate to the door.

4. In a door-hanger, the combination with 70 a door, a fixed track-bar and a rider-bar, of a connecting device comprising two vertical arms which straddle the said bars and are connected at their upper ends to the rider-bar, a base to which the lower ends of the 75 bar are connected and which rests upon the door, a plate extending between said arms at each side, said plate resting on the door and having recesses to receive the base and arms, and means for securing said plate to the door.

5. In a door-hanger, the combination of a fixed track-bar, a rider-bar to which a door may be connected, a series of balls between 80 said bars, a spacer interposed between said bars and having tapered openings therein within which the balls are loosely retained and may freely turn, and a pair of supporting and holding devices each comprising two connected horizontal portions, one of 85 said horizontal portions being secured to the upper surface of the spacer above one of the openings therein and having an opening of 90 less diameter than that of the balls, and the other horizontal portion extending under 95 the track-bar in close proximity thereto.

6. In a door-hanger, the combination of a fixed track-bar, a rider-bar to which the door may be connected, a series of balls between 100 said bars, a spacer interposed between said bars and having tapered openings therein said openings being of greater 105 diameter than the balls on the lower surface of the spacer and of less diameter on the upper surface thereof, and within which openings the balls are loosely retained and may freely turn, means for movably supporting 110 said spacer comprising two balls interposed between said spacer and track, and means for restricting upward movement of said spacer.

7. In a door-hanger, the combination of a fixed track-bar, a rider-bar to which a door may be connected, a series of balls between 115 said bars, a spacer interposed between said bars having upwardly tapering openings therethrough to loosely receive and retain the balls, the upper end of the openings being of less diameter than the balls, and means for movably supporting said spacer at its 120 ends on said track bar whereby it will not rest on intermediate balls.

8. In a door-hanger, the combination of a fixed track-bar, a rider-bar to which a door may be connected, a series of balls between 125 said bars, a spacer interposed between said bars having openings therethrough in which the balls are loosely received and may freely turn; the structure being such as to retain said balls against removal through 130

the tops of said openings, and separated antifriction means for supporting said spacer out of contact with said track bar.

9. In a device of the character set forth, a track having a deep groove in its upper face, a traveling carriage above said track, a series of balls received in said groove and supporting said carriage, a ball-carrier having openings of less diameter than said balls 10 and receiving each a portion of the upper hemisphere of one of said balls, whereby the latter are held against passing completely through said carrier, and means for holding said carrier against lifting relatively to said 15 track.

10. In a door-hanger, the combination of a fixed track-bar, a rider-bar to which a door may be connected, a series of balls between said bars, a spacer interposed between 20 said bars having upwardly tapering openings therethrough to loosely receive and retain the balls, the upper end of the openings being of less diameter than the balls, means for movably supporting said spacer at its 25 ends on said track bar whereby it will not rest on intermediate balls, and means for restricting upward movement of said spacer.

11. In a device of the character set forth, a track having a groove in its upper face, 30a carriage having a groove in its under face, a movable ball carrier interposed between the adjacent face of said track and carriage, balls loosely retained therein and engaging said track and carriage, and means for supporting said carrier from said track in posi- 35

tion to lessen the friction on said loosely held balls.

12. In a device of the character set forth, a track having a groove in its upper face, a carriage having a groove in its under face, 40 a movable ball carrier interposed between the adjacent face of said track and carriage, balls loosely retained therein and engaging said track and carriage, means for supporting said carrier from said track in position 45 to lessen the friction on said loosely held balls, and means for holding said carrier against lifting relatively to said track.

13. In a door hanger, the combination with a fixed track bar, of a rider bar, arms 50 straddling the track bar at different points and adapted to support a door below said track bar, a series of balls between said bars, a movable spacer interposed between said bars and adapted to travel between said pending arms, the said spacer having openings 55 therethrough in which the balls are loosely held, and means connected to said spacer at its ends beyond said straddling arms extending down below said track for 60 holding said carrier against lifting relatively to said track.

In witness whereof, I have signed my name to the foregoing specification in the presence of two subscribing witnesses.

MYRON COSSEY.
